UNITED STATES PATENT OFFICE.

WILLIAM E. WRAY, OF NEW YORK, N. Y.

THIRD-RAIL-RAILWAY SYSTEM.

SPECIFICATION forming part of Letters Patent No. 745,708, dated December 1, 1903.

Application filed March 26, 1903. Serial No. 149,610. (No model.)

To all whom it may concern:

Be it known that I, WILLIAM E. WRAY, a citizen of the United States, residing at New York, in the county of New York and State 5 of New York, have invented certain new and useful Improvements in Third-Rail Electric-Railway Systems, of which the following is a specification, such as will enable those skilled in the art to which it appertains to make and 10 use the same.

This invention relates to third-rail electric-railway systems; and the object thereof is to provide improved means for cleaning the third rail or removing therefrom snow, ice, 15 and other substances which may collect thereon and operate to prevent proper electrical connection therewith.

The invention is fully disclosed in the following specification, of which the accompanying drawings form a part, in which the separate parts of my improvement are designated by suitable reference characters in each of the views, and in which—

Figure 1 is a side view of a section of a 25 third-rail electric railway and showing a car or truck provided with my improvement; Fig. 2, a bottom plan view thereof, and Figs. 3 and 4 are side views of details of the construction shown in Fig. 1.

In the drawings forming part of this specification I have shown at *a* one of the main rails of a railway-track, and at *b* a third or electric rail, and I have also shown at *c* a car-truck, which may represent either a part of 30 an ordinary car or a part of a motor, and in the practice of my invention I mount beneath the truck a main shaft *d*, which is supported in hangers *e* and provided with journal-boxes *f*, through which the shaft *d* passes, and 35 placed in the hangers *e* over the journal-boxes *f* are springs *g*, which bear on said journal-boxes and serve to hold the shaft *d* in a depressed position or to press said shaft downwardly at all times. The shaft *d* is provided 40 at one or both ends with a gear-wheel *h*, and one of these wheels is adapted to bear at all times on the rail *b*. The truck *c* is also provided with other hangers *i*, in which are mounted journal-boxes *j*, through which is 45 passed a supplemental shaft *k*, and this shaft is provided with a gear-wheel *m*, which operates in connection with a corresponding gear-

wheel *n* on the shaft *d*, and mounted in the hangers *i* are contractile springs *o*, which are secured at one end to the top of said hangers 55 and at the lower end to the journal-boxes *j*, and these springs serve to pull the shaft upwardly at all times.

The shaft *k* is preferably a little below the shaft *d* and is provided at one or both ends 60 with a brush *p*, made, preferably, of steel wire or any other suitable material, and said hangers *i* and the shaft *k* are located rearwardly of the hangers *e* and the shaft *d*, or between said hangers *e* and the shaft *d* and the wheels *r* 65 of the truck. The truck *d* is also provided with a contact-arm *s*, provided with a brush, shoe, or similar devices *t*, also adapted to bear on the rail *b*, and by means of which electrical connection is made between the motor, 70 which is not shown, and the rail *b*. As thus constructed one of the wheels *h* is always in contact with the rail *b*, and the shaft *d* is revolved by friction occasioned by the pressure of said wheel on said rail. This operation 75 cuts up or breaks up any ice, snow, sleet, dirt, rust, or other substances that may collect on said rail, and the brush *p*, which also bears on said rail and which is rapidly revolved through the agency of the gear-wheels 80 *m* and *n*, brushes off or removes the said material from the surface of the rail and leaves the latter clean, so that the brush, shoe, or other contact device *t* may make perfect electrical contact therewith. It will also be noticed that the brush or brushes *p* revolve in 85 a direction opposite to that of the wheel or wheels *h*, and this also facilitates the operation of said brushes in cleaning the rail *b*.

My invention is in no way limited to the construction of a car or motor, and my improvement may be applied to any form or forms of cars or motors now in use, and said cars or motors may be provided at both ends thereof with my said improvement, and the object of providing the shafts *d* and *k* with gear-wheels *h* and brushes *p*, respectively, at both ends 95 thereof is to enable said cars or motors to be run in either direction.

Having fully described my invention, what I claim as new, and desire to secure by Letters Patent, is—

1. A railway car or motor adapted to be used on a third-rail electric-railway system

- and provided with hangers having a spring-depressed shaft provided with a gear-wheel adapted to travel on the third rail, and a spring-supported shaft mounted adjacent to 5 the first-named shaft and geared in connection therewith and provided with a brush also adapted to bear on said rail, substantially as shown and described.
2. A car or motor adapted to be used in connection with a third-rail electric-railway system, said car or motor being provided with hangers in which is placed a spring-depressed shaft, a gear-wheel connected with said shaft and adapted to bear on the third rail, a spring-supported shaft mounted adjacent to the first-named shaft and geared in connection therewith and provided with a brush adapted to bear on said rail, substantially as shown and described.

3. A car or motor adapted to be used in connection with a third-rail electric-railway system, said car or motor being provided with hangers in which is placed a spring-depressed shaft provided with a gear-wheel adapted to bear on the third rail, and a supplemental shaft 25 geared in connection with the first-named shaft and provided with a brush adapted to bear on said rail, substantially as shown and described.

In testimony that I claim the foregoing as 30 my invention I have signed my name, in presence of the subscribing witnesses, this 25th day of March, 1903.

WILLIAM E. WRAY.
